UNITED STATES PATENT OFFICE

128,059

DESIGN FOR A BUILDING BLOCK

Ernst Steinhard, London, England, assignor to The Marley Tile Company Limited, River-
head, Sevenoaks, England

Application July 30, 1940, Serial No. 94,046
In Great Britain May 31, 1940

Term of patent 14 years

To all whom it may concern:

Be it known that I, Ernst Steinhard, a citizen of the German Reich, residing at Green Gates, Craven Hill, London, W. 2, England, have invented a new, original, and ornamental Design for a Building Block, of which the following is a specification, reference being had to the accompanying drawing, forming part thereof.

The figure is a perspective view of a building block showing my new design. The side and end of the block not seen in the single view are the same as the side and end shown.

I claim:

The ornamental design for a building block,
as shown and described.

ERNST STEINHARD.
